ROBERT WILLIAM BAILY, OF OSKALOOSA, IOWA, ASSIGNOR TO INTERSTATE MANUFACTURING COMPANY, OF OSKALOOSA, IOWA, A CORPORATION OF IOWA.

HOT-AIR FURNACE.

1,114,669.

Specification of Letters Patent.

Patented Oct. 20, 1914.

Application filed April 24, 1914. Serial No. 834,124.

To all whom it may concern:

Be it known that I, ROBERT W. BAILY, a citizen of the United States, and a resident of Oskaloosa, in the county of Marion and State of Iowa, have made certain new and useful Improvements in Hot-Air Furnaces, of which the following is a specification.

My invention is an improvement in hot air furnaces, and has for its object to provide a furnace of the character specified, wherein the fire box or pot is lined with metallic liners or sections, instead of with fire brick, and wherein the sections are arranged in such manner that they may be easily removed and replaced, and wherein the said liners or sections are so arranged that they will assist in the complete combustion of the fuel.

In the drawings:—Figure 1 is a perspective view of the improved furnace looking from the front, and with parts broken away, Fig. 2 is a section taken substantially on the line 2—2 of Fig. 1, and looking in the direction of the arrow, Fig. 3 is an enlarged detail of a portion of the rear of the grate supporting frame, Fig. 4 is a similar view of the front of the supporting frame, Fig. 5 is a top plan view of a portion of one of the grate bars, Fig. 6 is a section on the line 6—6 of Fig. 5, looking in the direction of the arrow, Fig. 7 is a perspective view of a portion of the fire box from within, Fig. 8 is a section on the line 8—8 of Fig. 7, Fig. 9 is a side and front view of one of the supporting brackets for the lower portion of the lining, Fig. 10 is a front and side view of the upper bracket, Fig. 11 is a side view of a bolt, Figs. 12, 13 and 14 are transverse sections of the fire box and lining at different points, and Fig. 15 is a vertical section through the device for supplying water to the furnace.

The present embodiment of the invention comprises an outer casing A of approximately cylindrical form, having a cap A' at its top, and having a base T of angle material and of arc shape. An arc-shaped radiator B is arranged within the main casing near the top thereof, being supported in a manner to be presently de-

scribed, and the said radiator has a central rearwardly extending outlet pipe B', for connection with a flue, the said pipe passing through the wall of the outer casing A at 55 the rear thereof.

The radiator B has its ends at the front of the casing A, and the said ends are bent inwardly, and are provided with marginal flanges U, which abut against similar flanges U' at the outer ends of nipples D' extending laterally from the sides of the fire box or furnace proper D, near the front thereof, and the flanges are riveted together, as indicated more especially in Fig. 1. The fire box is approximately elliptical in cross section, or more nearly of horse shoe shape, the heel of the shoe being at the front, and at the said front the fire box is provided with an opening to which is connected a substantially rectangular frame C, the said frame partially closing the front, and providing openings for the admission of fuel and for the removal of ashes. The main casing A is also provided with an opening at its front, encircled by a frame A², and the frame is provided with extensions A³ extending radially inward, and abutting the sides of the fire box, to close the space between the fire box and the main casing at 80 this point. A door D² is hinged to the frame C, as indicated at D³, the said door closing the opening. A grate is provided, the said grate comprising a series of shafts F journaled in the fire box, in horizontal position, and in the same plane, and each shaft is provided with a series of substantially triangular extensions F'. It will be noticed that the corners of the grate bars are rounded, and the bars are similarly arranged on the shafts, so that any side of the bars may be brought upward to form a support for the fuel. Each of the shafts F is annularly reduced at its rear end, as shown at Fig. 2, and the shafts are journaled in grate supporting bars G at the rear of the fire box. The supporting bar is provided with open bearings G', and the reduced portions F² of the shafts fit within the bearings.

The bearings G' are reduced at their upper parts, as indicated in Fig. 3, so that the

shafts will not be easily disengaged. A supporting bar P is provided for supporting the front ends of the shafts, the said frame being arranged transversely of the door opening, and being provided on its under edge with notches or recesses P' arranged at spaced intervals, and at intervals corresponding to the spacing of the bearings G'.

5 A hook H is pivoted to the supporting bar P at each of the notches P', and the said hooks are adapted to engage beneath the shafts F, to support the said shafts for oscillating movement, as shown in Fig. 4. The front ends of the shafts are of triangular 10 cross section, as shown in Fig. 1, for engagement by a tool to oscillate the shafts, when it is desired to stir the fire. The casing of the fire box D is provided with a lining, shown more especially in Fig. 7. The lining is sectional, and each of the sections consists of a 15 plate E, of arc shape transversely to fit the inner face of the casing, and the plates are arranged with their side edges abutting, or the plates may be spaced apart a slight 20 distance, to permit the admission of air from the ash pit over the top of the fire.

25 Each of the plates E, as shown more especially in Figs. 12 to 14 inclusive is provided intermediate its side edges with a laterally offset portion E'. The portions E' are offset inwardly with respect to the plates and each of the said portions is shaped as indicated in Figs. 12 to 14, being of approximately equal depth from the bottom of the 30 plate to near the top, at which point it gradually decreases finally merging into the level of the plate.

35 A space is thus provided between the offset portion E' of each section of the lining 40 and the inner face of the casing of the fire box, and each of the sections is provided with a longitudinally extending series of 45 openings W at its upper end, for providing a communication between the said space or passage and the interior of the fire box. The sections are held in place by means of brackets Q and R shown in Figs. 9 and 10, the bracket Q being at the lower end of the section, and the bracket R at the upper end. 50 Each of the brackets R has its ends offset laterally in the same direction from the body and connected thereto, and each of the ends is provided with an opening R', for receiving rivets X to secure the said ends to the 55 rear face of the section, at the offset portion E'.

60 The body of each of the brackets R is provided with a key hole slot R², and each of the slots is adapted to permit the passage of the head of a bolt S connected with the casing of the fire box D. It will be noted that the head of each of the bolts is frusto-conical, and the large portion of the slot R² is downward in such manner that when the head is 65 passed through the slot at the lower end, and

the section is permitted to be moved downward the head will engage the small end of the slot to lock the section to the casing at the upper end of the section.

Each of the brackets Q consists of two 70 parallel portions offset laterally with respect to each other, one of the portions having an opening Q' for receiving a rivet X to connect the bracket to the section, and the other portion of each of the brackets is provided with 75 a longitudinally extending slot or recess Q³ for engaging the head of a bolt S. The bolts S are passed through the casing of the fire box D from within outward and are engaged by the nuts on the outer face of the said 80 casing.

The slots R³ and Q³ engage the heads of the bolts, to connect the sections to the casing. It will be noted from an inspection of Fig. 8, that at its lower end each of the sections is bent laterally inward away from the casing wall. An open passage is thus provided between each of the lining sections and the casing wall, the passage opening at the bottom of the section directly into the 90 interior of the furnace, and opening at its top by way of the openings W.

95 Any of the lining sections may be released from the fire box wall by pushing it upward, as indicated in Fig. 8. The sections are thus easily removed and replaced. A pan I is supported from the top of the outer casing A, by means of angle brackets O. Each of the said brackets has one of its portions secured to the top of the casing, and the other 100 portion secured to the pan, and the pan is thus supported by the top of the casing. The angle brackets are long enough to space the upper edge of the pan below the top, so that the water evaporated from the pan may 105 have free escape. A pipe K extends through the wall of the cap A', at the front thereof, over the pan, the inner end of the pipe delivering to the pan. The outer end of the pipe is connected with a funnel L secured 110 to the outer surface of the casing A and it will be evident that when water is poured into the funnel it will run into the pan.

115 A second pipe M is arranged below the pipe K, the said pipe opening at its inner end through the side wall of the pan, and at its outer end through an extension L' from the funnel. The extension L of the funnel is riveted to the casing wall, to hold the funnel in place. It will be noted from 120 an inspection of Fig. 1 that the outer casing consists in fact of two sections exclusive of the cap. The sections are connected together and the cap is connected to the upper section by means of arc-shaped strips A⁴. 125 One of the strips is arranged between the sections of the casing and the other strip is arranged between the upper section and the cap.

130 Each of the strips has a central bead, and

the bead is arranged between the meeting ends of the sections, and between the edge of the cap and the adjacent end of the upper section. The lining for the fire box, that is 5 the sections E are of wrought iron or steel, or of cast iron, and they are of sufficient thickness to enable them to withstand the destructive effect of the heat, while at the same time they are not too thick to prevent 10 the heating of the body of the casing D, to permit the heating of the air between the fire box and the outer casing. As is known, fire brick when used for the lining of fire boxes or fire pots act as non-conductors of 15 heat, insulating the fire from the casing wall, in such manner that that portion of the box or pot wall covered by the brick is of little or no value for heating purposes. In addition, the fire brick are necessarily of 20 such thickness that the capacity of the fire pot is materially reduced. Furthermore the fire bricks crumble away in use, and they are destroyed by the adhering clinkers and slag. Whenever a clinker or a piece of slag 25 adheres to the brick, a portion of the brick will come away when the clinker or piece of slag is dislodged. The metallic liners or sections cannot crumble away, and any adhering clinkers or slag act rather to protect 30 the liners or sections than to harm them.

Any individual liner or lining section may be removed at will, without disassembling the furnace. It is not even necessary to remove the casing or jacket in the 35 heating chamber, in order to permit access to the liners. The bolts S with their frusto-conical heads are first placed, after which the clips or brackets Q—R are riveted to the liners. The peculiar shape of the bolt 40 heads cooperates with the shape of the slots Q²—R² to wedge or clamp the heads tightly in the openings.

The sides of the liner section fit snugly against the inner face of the fire box or 45 casing from the top of the said liners to near the bottom, and the chamber formed between the liners and the casing wall permits the heated air to pass up through the said chamber and into the combustion chamber above the fuel. Thus the shape of the 50 liners provides in addition to the reinforcing of the liners means for providing for a more thorough combustion of the fuel. The unconsumed gases generated by combustion will 55 thus be mixed with the heated air rising through the recesses of the liners and entering the combustion chamber openings W. Thus complete combustion will be assured, resulting in economical operation.

60 The liners are also preferably spaced apart slightly at their side edges, to provide for the admission of air, and also to permit expansion when heated, and the bent out lower ends of the liners come directly above 65 the grate, serving the function of a grate

ring. As is known, incomplete combustion is shown by the escape of black smoke, and a large amount of the heating value of the fuel passes away into black smoke. With the particular arrangement of the liners 70 there will be no escape of black smoke, all of the carbon being consumed, so that combustion is smokeless.

The operation of the improved furnace is as follows:—With the grate in proper position, and the fire burning, the draft passes by way of the opening for the ash pit, through the burning fuel, and through the passages between the liners of the fire box wall, to the arc-shaped casing or heating 80 chamber B, from whence the draft passes by way of the flue. The heated air from the outer casing may be removed in any desired manner for use at distant points. The air so heated is moistened by the water in 85 the pan I, and the said pan may be easily supplied with water by way of the funnel L. While the method of fastening liners in place is preferred it is obvious that other methods may be used, the invention residing 90 in the particular form of liner section and their detachable connection with the shell or sides of the combustion chamber.

I claim:—

1. In a hot air furnace, a fire box, a grate arranged transversely of the fire box near its lower end, and a metallic sectional lining connected to the fire box above the grate, the sections of the lining being detachable, each of the said sections consisting of a plate 100 curved transversely to fit the inner face of the fire box, and having in its rear face a longitudinally extending groove opening at the lower end of the section and forming a rib on the opposite face of the section, said lower end being bent inward to extend above the grate, the said groove forming a passage between the section and the fire box wall from the bottom of the section to near the top thereof, and each section having 105 openings in the bottom of the groove at the top thereof, and means for detachably connecting the sections to the fire box wall, said means comprising a bracket secured to the section at the bottom of the groove and near the top thereof and having its intermediate portion offset outwardly away from the section and provided with a longitudinally extending key hole slot, a bracket secured to each section near the lower end and in the groove, each of the said last-named brackets having its lower end offset outwardly and provided with a longitudinally extending slot or recess, and bolts detachably connected with the fire box for engagement by the 110 brackets, each bolt having a frusto-conical head for engaging a notch or a slot.

2. In a hot air furnace, a fire box, a grate arranged transversely of the fire box near its lower end, and a metallic sectional lining 115

- connected to the fire box above the grate, the sections of the lining being detachable, each of the said sections consisting of a plate curved transversely to fit the inner face of the fire box, and having in its rear face a longitudinally extending groove opening at the lower end of the section and forming a rib on the opposite face of the section, the outer or rear face of each section fitting 5 against the fire box at each side of the groove, said lower end being bent outward to extend above the grate, the said groove forming a passage between the section and the fire box wall from the bottom of the section to near the top thereof, and each section having openings in the bottom of the groove at the top thereof, and means for detachably connecting the sections to the fire box wall.
- 10 3. In a hot air furnace, a fire box, a grate arranged transversely of the fire box near its lower end, and a metallic sectional lining connected to the fire box above the grate, the sections of the lining being detachable, each 15 of the said sections consisting of a plate curved transversely to fit the inner face of the fire box, and having in its rear face a longitudinally extending groove opening at the lower end of the section and forming a rib on the opposite face of the section, the outer or rear face of each section fitting 20 against the fire box at each side of the groove, said lower end being bent outward to extend above the grate.
- 25 4. In a hot air furnace, a fire box, a grate arranged transversely of the fire box near its lower end, and a metallic sectional lining connected to the fire box above the grate, the sections of the lining being detachable, each 30 of the said sections consisting of a plate curved transversely to fit the inner face of the fire box, and having in its rear face a longitudinally extending groove opening at the lower end of the section, the outer or 35 rear face of each section fitting against the fire box at each side of the groove.
- 40 5. In a hot air furnace, a fire box, and a sectional lining of metal for the fire box, each of the said sections consisting of a plate curved transversely to fit the inner face of the fire box, the plates being arranged vertically alongside each other, and with their adjacent edges spaced apart 45 slightly from each other, each plate having in its convex face a longitudinal groove extending from near the top to the bottom of the plate and forming a rib on the concave face, the rear face of each section fitting 50 against the fire box at each side of the groove, means for detachably connecting each section to the fire box, and each of the said sections having an opening at its top for placing the groove in communication with the interior of the fire box.
- 55 6. In a hot air furnace, a fire box, and a sectional lining of metal for the fire box, each of the said sections consisting of a plate curved transversely to fit the inner face of the fire box, the plates being arranged vertically alongside each other, and with their adjacent edges spaced apart 60 slightly from each other, each plate having in its convex face a longitudinal groove extending from near the top to the bottom of the plate and forming a rib on the concave face, the rear face of each section fitting against the fire box at each side of the groove, means for detachably connecting each section to the fire box, each of the said sections having an opening at its top for placing the groove in communication with the interior of the fire box, the lower end of 65 each of the said sections being bent out-

wardly to lie above the grate, the detachable connection comprising bolts connected with the fire box near the ends of each of the sections, each of the sections having brackets provided with offset portions having 70 openings for engagement by the heads of the bolts, the said heads being frustoconical and the openings of the brackets being of greatest width at their lower ends.

7. In a hot air furnace, a fire box, and a sectional lining of metal for the fire box, each of the said sections consisting of a plate curved transversely to fit the inner face of the fire box, the plates being arranged vertically alongside each other, and with their adjacent edges spaced apart 75 slightly from each other, each plate having in its convex face a longitudinal groove extending from near the top to the bottom of the plate and forming a rib on the concave face, the rear face of each section fitting against the fire box at each side of the groove, means for detachably connecting each section to the fire box, each of the said sections having an opening at its top for placing the 80 groove in communication with the interior of the fire box, the lower end of each of the said sections being bent outwardly to lie above the grate.

8. In a hot air furnace, a fire box, and a sectional lining of metal for the fire box, each of the said sections consisting of a plate curved transversely to fit the inner face of the fire box, the plates being arranged vertically alongside each other, and with their adjacent edges spaced apart 85 slightly from each other, each plate having in its convex face a longitudinal groove extending from near the top to the bottom of the plate and forming a rib on the concave face, the rear face of each section fitting against the fire box at each side of the groove, means for detachably connecting each section to the fire box, and each of the said sections having an opening at its top for placing the groove in communication 90 with the interior of the fire box.

9. In a hot air furnace, a fire box, and a sectional lining of metal for the fire box, each section consisting of a plate curved transversely to fit the inner face of the box, 95

100

the plates being arranged alongside each other with their long axes approximately vertical, each plate having its central portion spaced away from the fire box, from the bottom to near the top, and having openings through the section at the groove and near the top, the rear face of each section fitting against the fire box at each side of the groove.
